UNITED STATES PATENT OFFICE

GEORGE P. COLE, OF JOHNSTOWN, NEW YORK.

BUCKLE.

SPECIFICATION forming part of Letters Patent No. 398,028, dated February 19, 1889.

Application filed August 18, 1888. Serial No. 283,067. (No model.)

To all whom it may concern:

Be it known that I, GEORGE P. COLE, of Johnstown, in the county of Fulton and State of New York, have invented a new and Improved Harness-Buckle, of which the following is a full, clear, and exact description.

Reference is to be had to the accompanying drawings, forming a part of this specification, in which similar letters of reference indicate corresponding parts in all the figures.

Figure 1 is a front view of my improved harness-buckle. Fig. 2 is a rear view. Fig. 3 is an edge view. Fig. 4 is a longitudinal section, and Fig. 5 is a detailed perspective view of the buckle-wedge.

My invention is in the class of buckles having an adjustable wedge for clamping the strap or trace beneath a cross-bar of the buckle-frame.

20 The improvement will be hereinafter pointed out.

The body A of the buckle consists of a frame having side bars, *a*, end bars, *b* and *b'*, the central elevated cross-bar, *c*, side loops, *d*, and web *e*, extending across the buckle from one bar *a* to the other and provided with a slot, *f*. The end of the buckle-frame forming the bar *b* is bent rearwardly, and the end of the frame forming the bar *b'* is bent outwardly, and upon the said bar *b'* is formed a loop, *g*. Between the side bars, *a*, and upon the slotted web *e* is placed the wedge *B*, which is provided with a slot, *h*, corresponding with the slot *f* of the web *e*. The wedge *B* is also provided with a stud, *i*, which projects downward into the slot *f* of the web *e*.

The shank *j* of the buckle-tongue *C* extends through the slot *h* of the wedge *B* and through the slot *f* of the web *e*, and is either provided 40 with a nut, *k*, or with its equivalent burr held in place upon the said shank by riveting. The tongue *C* is provided with a shoul-

der, *l*, which rests upon the outer face of the wedge *B*, and the tongue is of sufficient length to engage the cross-bar *c*.

45 My improved buckle is more particularly designed for the traces of a harness. The trace is inserted underneath the bar *b'* and under the bar *c*, while the wedge *B* and the buckle-tongue *C* are drawn away from said bar as far as practicable, as shown by full lines, Fig. 4. (Such adjustment of the wedge and tongue is practicable by loosening the nut *k*.) After the end of the trace has been drawn through the buckle, as shown in dotted diagonal lines, Fig. 4, the tongue is pushed back until it enters a hole in said trace and comes in contact with the cross-bar *c*. Then the wedge is also forced back as far as practicable, when the nut *k* is tightened to 55 clamp both tongue and wedge in such position.

Having thus fully described my invention, I claim as new and desire to secure by Letters Patent—

1. The combination, with a buckle-body, *A*, 65 provided with the slotted web *e*, of the slotted wedge *B*, and the buckle-tongue *C*, having the shank *j* inserted in the slots of the said wedge and web, substantially as shown and described.

70 2. The combination, with the buckle-body *A*, having its ends curved in opposite directions and provided with the slotted web *e*, substantially as described, of the slotted wedge *B*, provided with a stud, *i*, and the buckle-tongue *C*, having the shank *j*, and furnished with the shoulder *l* and nut *k*, substantially as shown and described.

The above specification of my invention signed by me this 3d day of August, 1888:

GEO. P. COLE.
